US00D324369S

United States Patent [19]
Bushman et al.

[11] **Patent Number:** **Des. 324,369**
[45] **Date of Patent:** **** Mar. 3, 1992**

[54] **BATTERY CHARGER**

[75] Inventors: **Douglas C. Bushman, Houston; Jeffrey C. Barrus, Tomball, both of Tex.**

[73] Assignee: **Compaq Computer Corporation, Houston, Tex.**

[**] Term: **14 Years**

[21] Appl. No.: **430,232**

[22] Filed: **Oct. 31, 1989**

[52] U.S. Cl. **D13/107**

[58] Field of Search **D13/107, 108, 109, 120, D13/184; D14/253, 100, 101, 107; 320/2, 3, 4,**

[57] **CLAIM**

The ornamental design for a battery charger, as shown and described.

DESCRIPTION

FIG. 1 is a front isometric view of a battery charger showing our new design with both access doors in the fully open position;

FIG. 2 is a front isometric view of a battery charger showing our new design with both access doors in the fully closed position;

FIG. 3 is a right side elevational view thereof;

FIG. 4 is a front elevational view thereof;

FIG. 5 is a top plan view thereof;

FIG. 6 is a left side elevational view thereof;

FIG. 7 is a rear elevational view thereof;

FIG. 8 is a bottom plan view thereof;

FIG. 9 is a cross-sectional view thereof taken along line 9—9 of FIG. 5; and

FIG. 10 is a cross-sectional view thereof taken along line 10—10 of FIG. 5.
